US00D952132S

(12) **United States Design Patent** (10) Patent No.: **US D952,132 S**
(45) Date of Patent: **** May 17, 2022**

(54) **Facemask**

(71) Applicants: **Scott A. Cohen**, Portland, ME (US);
Michael B. Tybergheim, Roswell, GA (US)

(72) Inventors: **Scott A. Cohen**, Portland, ME (US);
Michael B. Tybergheim, Roswell, GA (US)

(73) Assignee: **AMERICAN BIOMEDICAL GROUP INC.**, Oklahoma City, OK (US)

(**) Term: **15 Years**

(21) Appl. No.: **29/753,729**

(22) Filed: **Oct. 1, 2020**

(51) LOC (13) Cl. **29-02**

(52) U.S. Cl.

USPC **D24/110.1**
